7 Claims. (CL 289—2)

1

The present invention relates to knot tying devices, and more particularly to devices for cutting and knotting packing means, such as pack-thread, twine, strings, bands or the like, which comprise a knotting plug provided with cutting means and with a brake for the packthread or the like.

Knot tying devices have already been proposed which are formed by a two part finger in which one of the two movable parts carries the brake and a cutting knife. These known devices present the disadvantage that the movable parts do not permit an independent adjustment of the brake and of the cutting knife.

According to the present invention the knotting plug is carried by a base and is formed at least in two parts, one of which is rigid with the base while the other part is movably mounted and bears against the fixed part.

The knotting plug has its exterior contour preferably formed in cone-shape. This shape is advantageous for the reason that sliding of the thread along the cone surface is favourably influenced. In a preferred embodiment of the device according to the invention the angle on the apex of the cone is approximately 30°. The cone-shaped plug preferably consists of three parts and is divided in such manner that one of the three parts comprises one half of the plug, while the two other parts comprise each 1/4 of the plug and the plug is cut along planes passing through the axis of the plug.

One of the three parts, conveniently that part which is formed from the half plug, is rigidly connected with the base in a preferred embodiment of the invention, while the two other parts are movable relatively to the fixed part and to the base. By means of a spring the two movable parts of the plug are yieldingly applied against the fixed part, and this spring pressure can be variable.

In this preferred embodiment one of the two movable parts carries the cutting knife while braking means are disposed on the other movable part. The height, at which the cutting knife and the braking means are disposed in the plug, is so chosen, that the cutting knife only becomes effective when the brake already has gripped and is holding the twine.

An advantageous construction of the knotting plug lies in the fact that it is formed hollow. The cutting edge of the knife and the brake surface are then so disposed along the walls of the cone-shaped plug, that they are not parallel, but enclose an angle one with another owing to the in-

2

clination of the surfaces of the plug. Such a disposition has the advantage that the twine tension increases during the cutting. The thread is pressed from above into the plug between the fixed portion and the two movable portions, for effecting the knotting. It is thus first gripped by the brake and shortly afterwards by the cutting knife. But since the cutting knife and the brake are always further spaced upon further downward movement, the twine is tensioned between the knife and the brake, so that a clean severing is insured.

Since the device principally serves for making carrying loops on paper bags or packages, it is convenient to construct it in such manner, that its operation is not hindered by the holding of the packages or the bags. For this purpose a package carrier can be associated with the twine knotter which carrier allows putting the package down during the utilisation of the twine knotter.

Finally it is also advantageous for the operation of the twine knotter, when there is provided a device for unwinding the twine from the twine ball. This device is advantageously provided with a brake which prevents the unwinding thread from automatically unwinding.

The accompanying drawing represents by way of example a preferred embodiment of the invention, without intention to limit the invention to the illustrated details.

Fig. 1 shows a knot tying device according to the invention in side elevation.

Fig. 2 shows the device in the plan view.

Fig. 3 shows the actual knot tier formed as a plug.

Fig. 4 is a section through the plug along the line IV—IV of Fig. 2.

Fig. 5 is a section through the plug along the line V—V of Fig. 2.

Fig. 6 shows the formed knot.

In the drawings, numeral 1 designates a fixed base, on which is formed the cone-shaped knotting plug. The plug consists of a portion 2 rigidly connected with the base and two portions 3, 3' which are movable relatively to the base 1. The angle at the vertex of the cone-shaped plug measures about 30°.

The plug portions 3, 3' are formed hollow as can be clearly seen in Fig. 5. By means of eyes 4, 4' and of a traversing pin 5, which is conveniently provided with a screw thread 6 at one end, while it carries a head 7 on the other end, the two portions 3 are laterally held together. The pin 5 provides at the same time a bearing on which the two plug portions 3, 3' can turn about the pin

5 as an axis. The bottom surfaces 45, 46 of the portions 3 are slightly tapered. Two balls 8 abut against the respective surfaces 45, 46 and are pressed upwardly by springs 9. The springs 9 are placed in bores 10 of the base 1 which are closed at the bottom by screws 11.

It is apparent from the drawing that the balls 8 yieldingly press the two movable plug portions, capable of turning about the pin 5, against the fixed portion 2 of the plug.

As may be seen in Fig. 4, one of the two movable portions 3' carries a cutting knife 12 which is secured by two screws 13. The blade of the cutting knife is downwardly inclined and engages a slot 14 of the portions 2 of the plug.

The other of the two movable portions 3 is formed as a brake. The surface 15, as well as the opposite surface 16 of the fixed portion 2 of the plug are roughened or knurled, in order to grip the thread. The cutting edge of the knife and the braking surfaces thus are disposed at an angle to each other.

As is visible from the drawing, the plug has its vertex provided with an entrance 17 which narrows downwardly. When the twine 18 is introduced into this entrance, it is first gripped by the brake 15, 16 and then it makes contact with the cutting knife 12. When the thread is pulled downwardly between the surfaces 15 and 16, the movable part 3 forming the brake is slightly turned backwards, whereby the pressure exerted on the thread by the action of the spring 9 increases. In this manner a safe cutting of the twine by the knife is insured, while at the same time the brake holds the thread. Since the cutting knife is inclined relatively to the brake, and the cutting knife and the brake are closer to each other towards the vertex of the plug than towards the base of the plug, the twine is tensioned between the brake and the cutting knife while being pulled downwardly.

A pin 19 is screwed in the base 1 of the plug and is secured therein by a set screw 20. This pin carries a plate 21 rigidly connected thereto and traversed by screws 22. These screws 22 serve for securing the device to a table, a wall board or the like. The board 23 is thus inserted into the space between the base 1 and the plate 21.

The plate 21 is secured to the pin 19 by the set screw 24. The lower end of the pin 19 carries a collar 25 secured by means of a screw 26. A second freely movable collar 27 is disposed above this collar 25 on the pin 19. This movable collar 27 is connected to the plate 21 by a spiral spring 28 surrounding the pin 19, which spring allows the collar 27 to effect a pivoting movement, but returns it to the original position when the pull exerted on the collar ceases.

From Figs. 1 and 2 it is apparent that the collar 25 rigidly connected to the pin 19 carries a pan-shaped part 29 of wire gratings, which constitutes one half of a holding basket for the packages. The movable collar 27 carries the second half 30 of the holding basket. The holding basket is advantageously made from strong wire and comprises finger-shaped extensions 31, 32 extending one between the others in the position of rest. When a pulling effort is exerted on the movable portion 30, the basket opens, the movable collar 27 turning about the pin 19. The package 33 is then placed into the basket and knotting of the carrying loop is effected by means of the plug. When the knotting is effected the package is raised from the holding basket by the formed loop. Owing to the tension of the spiral spring 28 each other.

28 the collar 27 and the part 30 move back to the position of rest.

An unwinding device for the twine is carried by the fixed collar 25 by the intermediary of an arm 34.

The unwinding device consists of two semi-spherical cups, one of which 35 is disposed on the arm 34. The other half 36 is placed over the first one. A twine ball 37 is placed within the cup and the end of the twine is pulled out through an opening 38 placed on top of the cup.

In order that the twine does not run back, a brake is disposed in the interior of the unwinding device, conveniently below the opening 38, the execution of the brake being recognisable for example from Figs. 1 and 2. It consists of a wire spring 39 which is bent like shears about two screw pins 40. The twine 18 is pulled between the shears and thereby braked.

20 For protecting the middle parts of the device (spring 28 and pin 19) there can be provided a protecting sleeve 41.

The described device principally serves when 25 packing articles of any kind. When a package or a bag is to be strapped by twine, first a piece of twine of appropriate length is cut off from the provision ball 37, it being possible to use the knife 12 of the plug 2, 3. This piece of twine is then used for strapping the package, and when

30 it is desired to provide the twine with a carrying loop, the package is brought into the basket 29, 30 and the two ends 18 of the twine (Fig. 1) are disposed about the plug in the manner 35 represented, and the end portion is introduced from above into the entrance 17 between the fixed part 2 and the movable parts 3 of the plug.

30 The two twine ends are thereby gripped and held by the brake 15, 16. When thereafter the two twine ends projecting from the plug are pulled downwardly in the direction of the arrow, 40 the two twines are cut through by the edge of the knife 12, while the ends are gripped by the brake and maintained. The package is now raised from the basket 29, 30, whereby the loop placed

45 around the plug is pulled off the plug, while it slides over the twine ends held in the brake. In this manner the knot is automatically formed, as is represented in Fig. 6. By means of a further pulling action exerted on the package, the knot tightens and finally the gripped twine ends are pulled out of the brake and the carrier loop is thus formed.

The device can also be used only for the preparation of the twine and for cutting it off. In 50 this manner of use the twine pulled off from the ball is cut to the desired length by pressing it into the entrance 17 of the plug, while the remainder of the twine is held fast by the brake and thus is made ready for the next use.

It is, of course, to be understood that the above 55 described structure is merely illustrative and in no wise limiting and that I desire to comprehend within my invention all modifications included within the scope of the appended claims.

I claim:

1. A device for tying knots in twine or the like, comprising a knotting plug, a base therefor, said plug including a fixed part rigid with the base and at least a movably mounted part, means for yieldingly applying said movable part against the fixed part, a cutting means for the twine disposed between said fixed and movable parts of the plug, and braking means for the twine formed between said parts of the plug applied against each other.

2. A knot tying device for tying knots in twine or the like, comprising a knotting plug, a base therefor, said plug including a fixed part rigid with said base and two movably mounted parts, means for yieldingly applying said movable parts against the fixed part, a cutting knife for the twine carried by one of said movable parts, and a brake for the twine formed between the other movable part and the fixed part of the plug.

3. A knot tying device for tying knots in twine or the like, comprising a cone-shaped knotting plug, a base therefor, said plug including a fixed part rigid with said base and two hollow parts hingedly mounted on the base, means for yieldingly applying the movable parts against the fixed part, a cutting knife for the twine carried by one of said movable parts and penetrating into a slot provided in the fixed part, and a brake for the packthread formed by cooperating surfaces of the other of said movable parts and of the fixed part, said knife having a cutting edge which is inclined relatively to the cooperating brake surfaces.

4. A knot tying device as claimed in claim 3, in which the angle at the vertex of the cone-shaped knotting plug measures approximately 30°.

5. A knot tying device as claimed in claim 3, in which the cooperating braking surfaces of the fixed and movable plug parts are roughened.

6. A knot tying device as claimed in claim 2, and comprising springs to yieldingly apply the movable parts of the knotting plug against the fixed part, and means for varying the pressure of the springs.

7. A knot tying device for tying knots in twine or the like, comprising a knotting plug, a base therefor, said plug including a fixed part rigid with said base and two movable parts hingedly mounted on the base, a cutting knife for the twine carried by one of said movable parts, a gripping brake for the twine formed between the other movable part and the fixed part, said base of the knotting plug being provided with a bore beneath each of the hingedly mounted parts of the plug, a spring disposed in each of said bores for yieldingly urging the movable parts against the fixed part of the plug, and means for varying the pressure exerted by said spring on the movable parts of the plug.
